R. G. NEWBORNE.

METHOD AND MEANS FOR REMOVING FOREIGN MATERIAL FROM TOBACCO SCRAP.

APPLICATION FILED FEB. 17, 1914.

1,164,953.

Patented Dec. 21, 1915.

UNITED STATES PATENT OFFICE.

ROBERT G. MEWBORNE, OF LOUISVILLE, KENTUCKY, ASSIGNOR TO THE KENTUCKY TOBACCO PRODUCT COMPANY, A CORPORATION OF NEW JERSEY.

METHOD AND MEANS FOR REMOVING FOREIGN MATERIAL FROM TOBACCO-SCRAP.

1,164,953.

Specification of Letters Patent. Patented Dec. 21, 1915.

Application filed February 17, 1914. Serial No. 819,158.

To all whom it may concern:

Be it known that I, ROBERT G. MEWBORNE, a citizen of the United States, residing at Louisville, county of Jefferson, and 5 State of Kentucky, have invented certain new and useful Improvements in Methods and Means for Removing Foreign Material from Tobacco-Scrap, fully described and represented in the following specification 10 and the accompanying drawings, forming a part of the same.

This invention relates to an improved method and apparatus for removing from tobacco scrap the foreign material, such as 15 stem shreds, fiber, feathers, paper, etc., which heretofore has been picked from tobacco scrap by hand.

I have discovered that such foreign material may be quite largely removed from 20 tobacco scrap by passing it down an inclined table, which is given a quick reciprocating movement longitudinally of the scrap feed, as by an eccentric, so as to form a vibrating shaking table, and providing the 25 table with one or more obstruction bars projecting upward therefrom and extending across the table, several such bars preferably being used. These obstruction bars break the tobacco up into sections and the 30 shaking table imparts a rolling or rotary motion to the section of tobacco between each two bars, so that the shreds, fiber, etc., cling together and gradually collect against the upper side of the lower obstruction bar 35 as a roll or rope of foreign material, over which the tobacco scrap passes into the next section. This roll or rope of foreign material is removed by hand when it has reached the desired size. I have found in 40 actual practice that there is hardly any tobacco caught in the roll or rope of foreign material, and that the foreign material is thus quite largely removed from the tobacco scrap.

45 I preferably treat the tobacco scrap, after leaving the shaking table, for further removal of whatever foreign material may remain in the tobacco scrap, by subjecting the tobacco scrap to the action of a roll, or preferably a plurality of rolls, provided with a surface acting to pick up the foreign material from the tobacco scrap, this surface preferably being formed by a layer of the foreign material itself, which is excellently 50 adapted for this purpose. The tobacco

scraps is preferably fed past the rolls on a feeding belt or other table moving below the rolls instead of running the rolls over the tobacco, and preferably suitable stirrers, such as suspended chains, or the like, with 60 their free ends lying on the belt, will be used between each pair of rolls so as to stir up the tobacco scrap and bring a fresh surface to the top after the tobacco layer has been partially cleaned by the preceding roll, 65 but this arrangement may be changed within in the broader features of the invention.

In carrying out the invention, the tobacco scrap is preferably fed from a hopper onto the upper end of the inclined shaking 70 table by some feed which delivers a uniform layer onto the table, and the shaking table between the obstruction bars is preferably perforated so as to form a screen by which the tobacco dirt and dust will be screened 75 out of the tobacco scrap as the latter passes over the table. The shaking table delivers onto a feeding belt or other moving table, above which are mounted the rolls above referred to, which are free to rotate with the 80 moving tobacco scrap, and are mounted to move away from the table or belt, as the rolls increase in size by picking up the foreign material from the tobacco scrap.

For a full understanding of the invention, a detailed description of the construction embodying the same in a preferred form will now be given in connection with the accompanying drawings, and the features forming the invention then specifically 85 pointed out in the claims.

In the drawings—Figure 1 is a sectional side elevation of a simple form of apparatus embodying the invention; Fig. 2 is a plan view of the same; Fig. 3 is a cross section 95 on the line 3—3 of Fig. 1; Fig. 4 is an enlarged detail section illustrating the action of the obstruction bars; Fig. 5 is a detail cross section on the line 5—5 of Fig. 1, illustrating the action of the rolls for picking 100 up foreign material; and Fig. 6 is a section of Fig. 5 taken longitudinally of the feeding belt.

Referring to the drawings, *a* is the inclined shaking table, to which the tobacco scrap is fed with practically uniform feed by star-wheel *b* in hopper *c* above the upper end of the table. The table *a* is shown as suspended by swinging hangers 10 on standards 11, and is given the desired vibrating 105 110

or shaking motion by eccentric 12 on shaft 13, connected to the table by link 14. The table is shown as having three obstruction bars *d*, although more or less may be used, and between the obstruction bars *d* the table is preferably perforated to form a screen *e*, below which is shown a pan 15 for catching the dust and dirt screened from the tobacco scrap. From the lower end of the table *a*, the tobacco scrap, largely cleaned by the action of the shaking table and obstruction bars, passes onto a moving table shown as a feeding belt *f* mounted on rollers 16. Above the belt *f* are mounted a series of rolls *g*, three being shown in the present case, although less or more may be used if desired, these rolls *g* being mounted in any suitable manner so as to be free to rotate as moved by contact with the tobacco scrap on belt *f* and being free to move away from the belt as the layer of foreign material thereon increases in thickness. In the construction shown, these rolls are simply slipped into vertically slotted supports 17, in which the rolls are free to move vertically. Between each pair of rolls *g* are mounted stirrers *h*, which in the form shown consist of metal chains arranged in series across the belt and suspended from a bar 18 carried by supports 19 on opposite sides of the belt, so that the ends of the chains *h* drag through the tobacco scrap as the latter is carried forward by the belt, thus stirring up the tobacco and bringing a fresh surface to the top for action of the next roll thereon.

The rolls *g* may be made in any desired manner and provided with any surface suitable to pick up foreign material from the tobacco scrap. With any such surface, the operation of the roll at once forms a layer of foreign material upon the roll, which is efficient for the purpose desired. The roll, therefore, preferably is formed with such a surface and may well consist of a light wooden roll prepared by coating it with glue and covering it with a thin layer of the shreds and fiber which are to be picked up from the tobacco scrap, this layer being stuck on by the glue. The drawings show a roll thus formed, 1 being the center wooden roll, and 2 the layer of shreds, fiber, etc., glued on the roll.

The operation of the construction will be understood from a brief description: The tobacco scrap *x* is fed from hopper *c* by star-wheel *b* onto the upper end of shaking table *a*, and then passes down the table over the successive obstruction bars *d*, the fine dirt and dust being screened out by screen *e* and collected in the pan 15. As the tobacco scrap passes over the successive obstruction bars *d*, it is divided into sections between the bars, to which the rolling or rotary motion is imparted by the vibrating table, with the result that the shreds, fiber, and other

foreign material cling together and gradually form a roll or rope of foreign material against the upper side of each lower obstruction bar of a pair, and over which roll or rope the tobacco scrap passes downward. This action of the obstruction bars and shaking table is illustrated in Fig. 4, in which a roll or rope of foreign material *y* is shown collected against the upper side of an obstruction bar with the tobacco scrap *x* passing over it. This roll or rope is allowed to form to the size found best in practice, and is then removed by hand. The tobacco scrap *x*, with the foreign material referred to largely removed from it, is fed from the lower end of shaking table *a* onto belt *f* in a substantially uniform layer, and is then carried forward by the belt beneath the successive rolls *g*, which further clean the tobacco scrap by picking up fully or largely the foreign material such as above described that may remain in the tobacco scrap as delivered to the belt. After the tobacco scrap *x* passes the first roll *g*, it is stirred by the chains *h* so as to bring a new surface to the top for the action of the second roll *g* and so on with the successive rolls and chains, the cleaned tobacco being finally delivered from the end of the belt *f*. In practice, it is found that the rolls may run up to the diameter of 12 inches or more, when the roll is removed from the table and the foreign material stripped off down to the original material held on by the glue, and the roll is then again ready for use and is returned to its bearings over the belt. In Figs. 5 and 6, one of the rolls *g* is shown operating on the tobacco scrap *x* upon belt *f*, with a layer of foreign material *z* of considerable thickness picked up by the roll.

It is found in practice that the foreign material collected by the obstruction bars *d* and rolls *g* contains practically no tobacco, and that the tobacco scrap delivered by the belt *f* is almost entirely cleaned from foreign material such as described.

It will be understood that the invention is not to be limited to the specific construction or arrangement of parts illustrated, but that widely different constructions may be used within the invention as defined by the claims.

What is claimed is:—

1. The method of removing foreign material, such as shreds, fiber, etc., from tobacco scrap, which consists in passing the tobacco scrap over a surface provided with one or more obstruction bars extending upward from the surface, and giving the surface a reciprocating motion during the forward movement of the tobacco scrap to collect the foreign material against the obstruction bars.

2. The method of removing foreign material, such as shreds, fiber, etc., from tobacco

scrap, which consists in passing the tobacco scrap over a surface provided with one or more obstruction bars extending upward from the surface, giving the surface a reciprocating motion during the forward movement of the tobacco scrap to collect the foreign material against the obstruction bars, and then rotating over the surface of a layer of scrap one or more rotating rolls 10 having a surface adapted to pick up such foreign material from the tobacco scrap.

3. The method of removing foreign material, such as shreds, fiber, etc., from tobacco scrap, which consists in passing the tobacco scrap over a surface provided with one or more obstruction bars extending upward from the surface, giving the surface a reciprocating motion during the forward movement of the tobacco scrap to collect 15 the foreign material against the obstruction bars, and then moving the tobacco scrap in a uniform layer past and in contact with a plurality of rolls having a surface adapted to pick up such foreign material 20 from the tobacco scrap, and stirring the tobacco scrap between the successive rolls to bring a new surface into position for the roll action.

4. In an apparatus for removing the foreign material, such as shreds, fiber, etc., from tobacco scrap, the combination with an inclined table having one or more obstruction bars extending upward from the bottom of the table, of means for giving 35 the table a reciprocating motion in the direction of movement of the tobacco scrap, whereby the foreign material is collected against the upper side of the obstruction bar or bars.

40 5. In an apparatus for removing the foreign material, such as shreds, fiber, etc., from tobacco scrap, the combination with an inclined table having a screened bottom and a plurality of obstruction bars extending upward from the bottom to divide the tobacco scrap into sections above the screen, of means for giving the table a reciprocating motion in the direction of movement of the tobacco scrap, whereby the foreign material is collected against the upper side of the obstruction bar or bars.

45 6. In an apparatus for removing the foreign material, such as shreds, fiber, etc., from tobacco scrap, the combination with an inclined table having one or more obstruction bars extending upward from the bottom of the table, of means for giving the table a reciprocating motion in the direction of movement of the tobacco scrap, whereby the foreign material is collected against the upper side of the obstruction bar or bars, a support to which the tobacco scrap passes from the table, one or more rolls having a surface adapted to pick up such foreign material, and means for rotat-

ing the rolls over the surface of the tobacco scrap on the support.

7. In an apparatus for removing the foreign material, such as shreds, fiber, etc., from tobacco scrap, the combination with an inclined table having one or more obstruction bars extending upward from the bottom of the table, of means for giving the table a reciprocating motion in the direction of movement of the tobacco scrap, whereby the foreign material is collected against the upper side of the obstruction bar or bars, a traveling table or belt to which the tobacco scrap passes from the inclined table, and a plurality of rolls mounted to rotate in contact with the tobacco scrap carried by the table or belt, said rolls having surfaces adapted to pick up such foreign material and being free to move away from the table as the layer of foreign material increases in thickness.

8. In an apparatus for removing the foreign material, such as shreds, fiber, etc., from tobacco scrap, the combination with an inclined table having one or more obstruction bars extending upward from the bottom of the table, of means for giving the table a reciprocating motion in the direction of movement of the tobacco scrap, whereby the foreign material is collected against the upper side of the obstruction bar or bars, a traveling table or belt to which the tobacco scrap passes from the inclined table, a plurality of rolls mounted to rotate in contact with the tobacco scrap carried by the table or belt, 90 said rolls having surfaces adapted to pick up such foreign material and being free to move away from the table as the layer of foreign material increases in thickness, and stirrers between the rolls for bringing a 100 fresh surface into position for the roll action.

9. In an apparatus for removing the foreign material, such as shreds, fiber, etc., from tobacco scrap, the combination with an inclined table having a screened bottom and a plurality of obstruction bars extending upward from the bottom to divide the tobacco scrap into sections above the screen, of means for giving the table a reciprocating motion 110 in the direction of movement of the tobacco scrap, whereby the foreign material is collected against the upper side of the obstruction bar or bars, a traveling table or belt to which the tobacco scrap passes from the inclined table, and a plurality of rolls mounted to rotate in contact with the tobacco scrap carried by the table or belt, said rolls having surfaces adapted to pick up such foreign material and being free to move away from 120 the table as the layer of foreign material increases in thickness.

10. In an apparatus for removing the foreign material, such as shreds, fiber, etc., from tobacco scrap, the combination with an in- 130

clined table having a screened bottom and a plurality of obstruction bars extending upward from the bottom to divide the tobacco scrap into sections above the screen, of means 5 for giving the table a reciprocating motion in the direction of movement of the tobacco scrap, whereby the foreign material is collected against the upper side of the obstruction bar or bars, a traveling table or 10 belt to which the tobacco scrap passes from the inclined table, a plurality of rolls mounted to rotate in contact with the tobacco scrap carried by the table or belt, said rolls hav-

ing surfaces adapted to pick up such foreign material and being free to move away 15 from the table as the layer of foreign material increases in thickness, and stirrers between the rolls for bringing a fresh surface into position for the roll action.

In testimony whereof, I have hereunto 20 set my hand, in the presence of two subscribing witnesses.

ROBERT G. MEWBORNE.
